UNITED STATES PATENT OFFICE.

SAMUEL G. LEITCH, OF SOMERVILLE, MASSACHUSETTS, ASSIGNOR TO CARTER, RICE & COMPANY, INCORPORATED, A CORPORATION OF MASSACHUSETTS.

STAY-STRIP.

No. 853,094.

Specification of Letters Patent.

Patented May 7, 1907.

Application filed August 10, 1906. Serial No. 330,062.

To all whom it may concern:

Be it known that I, SAMUEL G. LEITCH, a citizen of the United States, residing at Somerville, in the county of Middlesex and State of Massachusetts, have invented a certain new and useful Improvement in Stay-Strips, of which the following is a specification, reference being had therein to the accompanying drawings.

In the making of paper boxes in which a stay strip is employed to bind together two adjoining sides of the box, the strip is usually glued or pasted partly to one of said adjoining sides and partly to the other and, therefore, has to be bent at a right angle in order to lap over onto the two sides. Stay strips of various kinds for this purpose have been made, but difficulty has been found in bending or folding the stay strip neatly and accurately along a line parallel with its sides which is necessary in order to make a good piece of work. When the stay strip is put on by machine, it is sometimes the practice to crease the strip along the intended folding line in order to enable it to be accurately folded. Sometimes this is done by means of a creasing device connected with the machine which applies the stay to the box, that is by running the flat strip over a creasing device just before it reaches the box. Sometimes this has been done by forming a longitudinal crease or groove in the face of the stay strip. This latter method is somewhat objectionable as it tends to weaken the stay strip along the folding line.

One object of the present invention is to provide a stay strip indented in such a way that it will more readily fold along the particular line desired without creasing it along the folding line or in any other way weakening the strip along the said folding line, and at the same time to increase the flexibility.

The invention consists essentially in forming in one face of the strip a series of depressions or indented diagonal lines on either side of the said intended folding line and slanting in opposite directions from each other, that is at an angle to each other, the apexes of the angles formed by the junctions of the oppositely inclined indented lines being in a straight line along which the strip will readily fold.

The invention will be fully understood from the following description taken in con-

nnection with the accompanying drawings, 55 and the novel features are pointed out and clearly defined in the claims at the close of the specification.

In the drawings,—Figure 1 is a perspective view of a coil of stay strip embodying my invention, partially uncoiled and showing the gummed face thereof with the diagonal lines of indentations. Fig. 2 is a longitudinal central section of a piece of the stay strip on an enlarged scale from Fig. 1, the section being taken through the points of junction of the two oppositely inclined series of indented lines. Fig. 3 is a perspective view showing the strip partially applied to the corner of a box. Fig. 4 is a longitudinal section showing a modification in which the diagonal lines cut through the adhesive. Fig. 5 is another modification, showing the indented lines formed in the back face of the strip.

Referring to the drawings,—1 represents 75 the stay strip which, for convenience in use, is preferably wound into a coil 21. The body or backing 2 of the strip is composed of cloth or paper or other suitable material and has upon one face a coating 3 of adhesive material of suitable composition which may be applied in any well known way and dried. There is formed in one face of the strip, preferably in the gummed face, if the invention is used with gummed stay strip, as shown in 80 Figs. 1 and 2, a series of indented lines 4, 4, on opposite sides of the intended folding line of the strip which, as shown in the drawings, is the median line lengthwise of the strip, as it is usually intended to fold the strip along 90 the middle. These lines are formed at an angle with each other and with the intended folding line, and preferably connect with each other at their inner ends, forming an angle 5 at the point of junction, the apexes of 95 all of these angles being a straight line which is the folding line.

The lines 4, 4, may be formed in any way suitable or convenient, either by pressure as by a wheel having wing flanges which are disposed in angular relation to each other as the lines to be formed, or by a die or by cutters which cut through the film of adhesive. If formed by pressure, the indentations might be as shown in Figs. 1 and 2 in which a depression 100 is formed on one side and a corresponding bulge 6 on the opposite side. If the diagonal lines are formed by cutting through the film

of adhesive, as shown by lines 7 in Fig. 4, there would not necessarily be any bulging on the back face.

It is found in practice that the strip will readily fold along the imaginary line joining the apexes 5 of the angles formed by the oppositely inclined diagonal lines. At the same time there is no weakening of the strip along the said line.

10 Heretofore in stay strips of this general character, it has been found that when employed to stay both the outside and the inside of the corner to a box, the stay strip has a tendency to spring out from one side or the other of the box owing to the fact that the gum does not set sufficiently quickly. My present invention renders the stay strip flexible at the point where the bend over the edge of the box occurs, so that there is no 20 tendency on the part of the stay strip to become displaced or spring out, and it remains fixed in place. This fixing of the stay-strip occurs without the necessity of holding the stay strip in position or very great pressure to 25 be exerted by the corner staying machine which applies the stay strip to the box.

The formation of lines which cut or break through the adhesive film, when the invention is used on gummed stay strip, causes the 30 backing to more readily absorb the moisture, throughout the strip, as these lines extend laterally the entire width of the strip and may be placed at close intervals. After the strip is applied to the box, it dries quickly.

35 While it is preferred to have the diagonal lines of indentations in the gummed face of the strip, they might be made in the back face as shown in Fig. 5 and still come within the scope of my invention, although I do not 40 consider this as desirable. While I have shown the indentations in the gummed face of the strip in the form of diagonal straight lines, it will be understood that the series of 45 diagonal lines may be made from somewhat curved or irregular lines, all of which have

the same general direction as the straight lines, in place of using lines which are absolutely straight.

I claim as my invention:

1. The improved corner stay strip having 50 in one face thereof two series of diagonal indented lines at an angle to each other whose proximate ends terminate in the intended folding line.

2. A corner stay strip for boxes and the 55 like having upon one face a coating of adhesive substance and having in a face thereof a series of diagonal indented lines on each side of the intended folding line, the lines on opposite sides of the intended folding line being at 60 an angle to each other.

3. A corner stay strip for boxes and the 65 like having upon one face a coating of adhesive substance and having in one face thereof a series of indented diagonal lines on each side of the intended folding line, the indented lines on opposite sides of the intended folding line slanting in opposite directions, the inner ends of those on one side of the intended folding line being connected with the 70 inner ends of those on the other side of the intended folding line, the apexes of the angles formed by the junctions of the lines in the two series being in a straight line which forms the intended folding line. 75

4. A corner stay strip for boxes and the like having upon one face a coating of adhesive substance and having in the gummed face thereof a series of diagonal indented lines on either side of the intended folding line, 80 the diagonal indented lines on opposite sides of the intended folding line being at an angle to each other.

In testimony whereof I affix my signature, in presence of two witnesses.

SAMUEL G. LEITCH.
